UNITED STATES PATENT OFFICE.

ERNEST W. PRIGAN, OF INDIANAPOLIS, INDIANA, ASSIGNOR TO H. C. NAYLOR AND S. H. KEENEY, OF INDIANAPOLIS, INDIANA.

ELECTRIC SWITCH STRUCTURE.

1,382,385.

Specification of Letters Patent. Patented June 21, 1921.

Application filed November 30, 1917. Serial No. 204,714.

To all whom it may concern:

Be it known that I, ERNEST W. PRIGAN, a citizen of the United States, residing at Indianapolis, in the county of Marion and 5 State of Indiana, have invented certain new and useful Improvements in Electric Switch Structures, of which the following is a specification.

My invention relates to improvements in 10 electric switch structures with coöperating locks.

One of the objects of my invention is to provide an electric switch, for controlling one or more electric circuits; for coincidentally rotating a spindle or valve stem to manipulate a valve, or to move a bolt or the like, and a coöperating lock, preferably of the permutation type, for locking and unlocking the movable instrumentalities to 20 prevent unauthorized use of the circuit or other objects controlled by said movable switch member.

Other, further and more specific objects 25 of my invention will become readily apparent to persons skilled in the art, from a consideration of the following description taken in conjunction with the drawings, wherein:—

Figure 1 is a section of the device taken 30 on line 1—1 of Fig. 4.

Fig. 2 is a bottom view of the upper part 35 of the switch and lock casing.

Fig. 3 is an axial section taken on line 40 3—3 of Fig. 1.

Fig. 4 is a plan view of the lower part 45 of the switch and lock casing showing the mechanism in "locked" position.

Fig. 5 is a similar view showing the parts 50 in "unlocked" position.

Fig. 6 is a diametric section showing also, 55 in plan view, several of the tumblers of the lock.

Fig. 7 shows the device applied to an 60 automobile to guard the electric circuits and 45 the gas line.

Fig. 8 is a dial and spindle for manipulating 65 the tumblers of the lock from the dash board of the vehicle.

Fig. 9 is a perspective view of a sleeve 70 upon which the tumbler disks of the lock are rotatably mounted.

In all the views the same reference characters 75 refer always to the same parts.

In the drawings I have illustrated one 80 embodiment which my invention may take,

reserving, however, the right to vary or modify the form and arrangement or disposition of the parts within the scope of the appended claims.

My improved lock structure is adapted 60 and arranged for closing one or more electric circuits, when the switch is "unlocked" and for opening said circuit or circuits so as to render them inoperative when the device is "locked."

Simultaneously with the movements of the switch member I may move other instrumentalities to close or open a valve; move a bolt, or to accomplish other similar results. Thus in the illustrative exemplification, a rotatable spindle, when released by the lock serves as an operative medium for moving a switch member and for opening and closing the valve. These agencies are so adjusted, with respect to each other, that 75 a given movement of the spindle will open (or close, as the case may be) a valve, and the same extent of movement will coördinately open or close one or more electric circuits.

The casing inclosing the switch, valve and lock structure, consists of two parts, the top part 15 and the lower part 16, adapted to be held together by screws 18, or the like. An annular, projecting hub 17, of 80 the lower portion of the casing, is bored to contain a valve 19. The upper end of the valve stem 20 has mounted on it, within the casing 23, a slotted arm 24 provided with a hub 25 having a set screw 26 passing therethrough into contact with the stem 20. A bore 27 flanks the bore in which the valve 19 is contained, and is screw threaded, as at 28 and 29, for the screw threaded fittings 30 and 31, respectively. These fittings are 85 connected to the sections 32 and 33, respectively, of the line of pipe which conveys the gasoline from a suitable reservoir to the carbureter 34, adapted for use with the engine shown. The upper portion 15, of the casing 90 is provided with a central hub 36 through which passes a spindle 37, carries on its lower end the tumbler disk 38 having an angular perforation 39, whereby it may be secured to the lower end of the spindle 37, 100 as by a screw 40. The tumbler 38 is therefore fixed to the spindle 37 so that it always rotates positively therewith. It is provided with a notch 41 having an oblique or tangential boundary 42, and an abrupt shoul-

105 110

der 43. Projecting downwardly, from one side of the slot 41, is a pin 44, for engagement with a tumbler disk 46 which rotates with tumbler disk 45 freely upon the 5 sleeve 47.

Rising centrally of the chamber 23, within the two part casing, is a stud 48 which is coaxial with the bore in which the spindle 37 is rotatable. A disk 49 of insulating material, is centrally bored to receive the lower end of the sleeve 47. This disk carries a plate 50 having a part 51 projecting from one side of the axis and secured together by rivets or screws 52, so that the two plates 10 may be rotated together, when occasion requires. Pivoted on the stud 53, which is secured to the projection 51 of the plate 50, is a dog 54, having a head 55 which is capable of substantially radial movement, 15 with reference to the disk axis or stud 48. A spring 56, having one of its ends secured to a small stud 57 and the other end to the head 55 of the dog 54, yieldingly holds the head of the dog on the peripheral surfaces 20 of the disks 38, 45 and 46. When the notches 41, 57 and 58 of the disks 38, 45 and 46, respectively are brought into transverse coincidence, as shown in Fig. 4, the spring 56 will push the head 55 of the dog, into the 25 space in the tumbler disks left vacant by the notches. When the parts occupy this position, as shown in Fig. 4, then upon rotation of the spindle 37 to the right, the head 55 of the dog will engage the shoulders provided by the notches in the tumbler disks, 30 and the plates 49 and 50 may thereby be rotated to a position limited by a stop pin 60 which projects vertically from the floor of the lower part 16 of the casing. Projecting upwardly from the floor is another 35 segmental-shaped stop 61, to limit the movement of the disks 49 and 50, in the opposite direction, as shown in Fig. 5. A pin 62 projects upwardly from the plate 49 and enters the slot of the arm 24, by means of 40 which the valve 19 is oscillated, so as to cut off the supply of liquid fuel that normally passes through the sections 32 and 33 of the fuel pipe, when the system is rotated 45 to the right, and whereby the valve is moved in the opposite direction to open communication between the pipe sections and close said electric circuits when the system is turned to the left, as clearly shown in 50 Figs. 4 and 5.

When it is desired to move the disks 49 and 50 to the left, to open the valve and to unlock or close the circuits, to be hereafter described, the oblique wall 42 of the notch 60 41, in the disk 38, will lift the head 55 of the dog, out of the slots in which it has been placed so that it is then in position to ride on the peripheral surfaces of the three disks. After the head has been raised, in 65 the manner described, out of the notches 41,

57 and 58, the pin 44 on the disk 38 will engage the upwardly extending pin 65 on the middle disk 45, which is in the circumferential path of the pin 44, as usual in commutation locks, thereby moving the notches 70 out of register and destroying the combination which may again be brought into registration by the usual procedure in the operation of permutation or combination locks, through the instrumentalities of the disks 75 38, 45 and 46 and the respective pins 44, 65 and 66.

The series of holes, placed around and near the periphery of the disks 45 and 46, are for the purpose of accommodating the 80 pins 65 and 66 when moved into new locations when it is desirable to change the combination of the lock, as usual in locks of this character.

Projecting radially from the casing members 15 and 16, and preferably as integral parts of the respective members are two-part cup members 67 and 68. These members are all alike and are adapted to register, when the two parts of the casing are in 90 proper assembled relation, and therefore I have marked the semi-cup members on the upper part of the section by the reference character 67 and the corresponding cup members, on the lower section 16, with the reference character 68. Each of the cup members contains a two part insulation cup member 69 and 70, in the upper and lower members 15 and 16, respectively. Each of the cup members is perforated, as at 71, and 72, 100 in the upper and lower parts 15 and 16, to provide an opening for metallic conduits 73. Each of the cup members in the lower part of the casing is provided with insulated, electric, yieldingly movable spring contacts, 105 which are all alike in every respect, and I will, therefore, describe one and mark the others with corresponding reference characters. These contacts are contained solely in the lower part of the casing, but equally 110 in the respective cup members of said casing parts. A screw threaded insulating sleeve 75 projects into each cup member sufficiently to prevent the nut 76 from touching the metallic part of the casing. A stud 77 115 having an axial cavity in its inner end is secured within the screw threaded sleeve 75 and is provided with a radially projecting threaded stem 78 for the nuts 76 and 79 to which the wires 80 of the respective circuits 120 are to be connected. The inner end of the stud 77 is bored for an axial movable contact member 81 which is yieldingly held inwardly by a spring 82. The member 81 is provided with a transversely extending pin 125 83 which moves in the transverse slot 84. A number of other contacts 86, 87, 88, 89 and 90, may be spaced around the casing and project into the chamber, within the casing, for the terminals of as many circuits as de- 130

sired, within the capacity of the device. Contacts 81 and 86 are for the accommodation of one circuit and the contacts 87 and 88 are for the accommodation of another circuit and the contacts 89 and 90 are for accommodation of another circuit, therefore the device, as shown, will open three circuits, when the mechanism is in locked position, thereby preventing the unauthorized use of three circuits that may be concomitant parts of an automobile starting system. Mounted upon the disk 50, and carried therewith, are segments of conducting material for the purpose of bridging the respective pairs of contacts when it is desired to close the circuit therebetween. The segment 91 will close the circuit between the yielding contacts 81 and 86, and at the same time the segment 92 will close the circuit between similar contacts 87 and 88 while the segment 93 will close the circuit between the contacts 89 and 90 when the parts are in the position shown in Fig. 4. When the parts are moved, into the positions shown in Fig. 5, these bridging segments are disconnected from the respective contacts and the circuits are thereby opened and when the circuits are opened the valve 19 is closed, by the same major instrumentality that moves the said circuit-opening mechanism.

The plate 49 is provided with inwardly extending tongues 95, that enter the diametrically opposite notches 96 in the sleeve 47 to prevent the sleeve from rotating. Separating washers 98 and 99 are placed between the tumbler disks 45 and 46 and are placed below the washers so that rotation of the respective disks will not be communicated to each other. Connected together, by universal joints 104, and communicating with a horizontally placed spindle 105 is a three part rod which is connected with a twirling knob 106 that may be placed upon the instrument board 107 of an automobile for operating the tumbler disks and subsequently rotating the circuit closing and valve closing means. The twirling knob 106 carries a dial 108 that is rotated therewith with reference to a fixed point or index 109. A similar dial, 110, may be fixed to the hub 36, of

the instrument, and a pointer or index 111, may be fixed to the rotatable spindle 37. Either dial and index may be used and different numerals for moving the tumbler disks to the same position may be indicated on the respective dials when desired.

The conduit tubing 73, through which the wires are carried into the chamber within the casing, is provided on its inner end with a washer 73', so that the conduits cannot be pulled out of the orifices in which they are contained, when the two parts 15 and 16 of the casing are put together.

Having described my invention, what I claim is:—

1. In a device of the character described comprising a two-part casing containing a circular chamber and a plurality of radially-projecting terminal-encompassing cups, each for inclosing an electric terminal; a circuit terminal within each cup, having a contact extending into the chamber; a rotatable member within said chamber, carrying connectors to connect said terminals in pairs, when rotated; operating means extending outside of the chamber to rotate said rotatable member and a permutation lock for connecting and disconnecting said operating means to said rotatable means.

2. A device of the character described comprising a two-part casing containing a circular chamber and a plurality of radially-projecting terminal-encompassing cups, a circuit terminal within each cup, having a contact extending into the chamber; a rotatable member within said chamber, carrying connectors to connect said terminals in pairs, when rotated; a combination lock, having a member connected with said rotatable member and another member connected to an operating means, for operating the tumblers of said lock, and subsequently to rotate said rotatable member.

In testimony whereof I hereunto set my hand in the presence of two subscribing witnesses.

ERNEST W. PRIGAN.

In the presence of—

HARRY A. FENTON,
EDWIN STEERS.
